UNITED STATES PATENT OFFICE.

LUCIUS F. HURD, OF LEE, MASSACHUSETTS.

HOLDER FOR LETTER-FILES.

SPECIFICATION forming part of Letters Patent No. 407,011, dated July 16, 1889.

Application filed November 6, 1888. Serial No. 290,114. (No model.)

To all whom it may concern:

Be it known that I, LUCIUS F. HURD, a citizen of the United States, and a resident of Lee, Berkshire county, Massachusetts, have 5 invented an Improved Holder for Letter-Files, of which the following is a specification.

The object of my invention is to provide a letter or bill file case or box with a holding or retaining attachment of such a character that 10 it is adapted to receive and hold a number of different forms of binding devices for the indexed sheets.

In the accompanying drawings, Figure 1 is a perspective view of a letter or bill file case 15 or box, shown open and with the indexed sheets in place ready for the reception of the letters, bills, or other documents to be filed away. Fig. 2 is a perspective view, drawn to a larger scale, showing my improved retainer 20 with a detachable binding-pin. Fig. 3 is a side view of the same with the pin locked in place and a portion of the case and leaves or sheets of the file in section. Fig. 4 is a perspective view, partly in section, of my im- 25 proved retainer, showing another form of binder with its leaves in position in the holder. Fig. 5 is a side view of my retainer with a portion of the case in section, showing still another form of binder for the leaves in 30 position in the holder.

In the drawings I have shown my improved retainer as adapted to be combined with three well-known forms of binding or uniting devices for the indexed leaves or sheets, and 35 it is also so constructed that it will not interfere with the use in the case of indexed leaves without means for uniting them together.

In Fig. 1, A represents any well-known 40 form of filing case or box with a hinged side or top lid a, and a hinged flap b, while D represents the series of indexed leaves or sheets between which the letters, bills, or other documents are to be filed away. In this figure I 45 have represented a pin e in a recess in the back of the case as a means of loosely binding or uniting the indexed leaves together, this pin passing through elongated openings in the tabs d, fastened to the backs of the sev- 50 eral leaves or sheets; but, as will be hereinafter seen, my improved retainer is so con-

structed that it may be used with other forms of devices for uniting or binding the indexed leaves together. I prefer to construct my improved retainer of sheet metal. The body is 55 to be secured to the inside back of the case by suitable screws, nails, or other fastening devices in the upright position shown in Fig. 2. This retainer F has at one end a bent foot-piece F', which in this instance is at the 60 bottom of the case when the latter lies flat. A portion of this foot-piece is so raised as to form a shoulder f, and consequently a groove or recess f', between this shoulder and the body or back of the retainer. In the elevated 65 portion of this foot-piece is formed a cross-shaped slot g, for the purpose hereinafter described.

At the opposite or upper end of the retainer F is formed a top piece F², which has 70 in it a central notch h, which is slightly widened out at its open end, as shown in Fig. 2. To the upper side of this top piece F², I pivot or hinge a handled retaining-catch H, of such a character that by swinging it around 75 in the direction of the arrow it can be made to close the open end of the notch h. Immediately over the top of this notch and at a suitable distance above it is a bent retaining-finger h', for a purpose explained hereinafter. 80

The top piece F² of the retainer is also provided on its under side with a spring catch or catches h², leaving between their ends and the body of the retainer a space about equal to the width of the groove f' at the bottom of 85 the retainer, for a purpose hereinafter described. For the purpose of economical construction these catches h² may be formed by cutting or stamping them up from the body of the metal, in the manner which will be 90 readily understood on reference to Fig. 2.

If the indexed leaves or sheets to be filed away are of that well-known form in which they have perforated tabs at their rear edges for the passing of a retaining-pin through 95 them, as shown in Fig. 1, the retaining-pin is made of the character shown in Fig. 2, and is combined therewith in the manner which I will now explain. This retaining-pin e, Figs. 2 and 3, is made with a T-head or other suitably-shaped head e' at one end, and, either before or after being passed through the open-

ings in the tabs on the indexed leaves, its **T**-head is inserted into the cross-shaped slot at the bottom of the retainer **F** by holding the retainer at an angle, passing the **T**-head 5 through the corresponding portion of the cross-slot, and then turning the pin up to the position shown by dotted lines in Fig. 2 and by full lines in Fig. 3, so that the upper end of the pin will rest in the enlarged open end 10 of the notch **h** at the top of the retainer. The diameter of the pin at that point is such that it will not pass to the bottom of the slot, but is held firmly in the enlarged portion of the slot by turning the catch **H**, so as to close 15 the open end of the notch. If the indexed leaves did not have their tabs passed over the retaining-pin **e** before the **T**-head of the latter was passed into the cross-slot, they should be passed over the pin, of course, 20 before the latter is locked in the retainer, as shown in Fig. 3. Another well-known form of binding device for these loose leaves is that illustrated in Fig. 4. This consists of an elongated link or slotted plate **K**, 25 having one leg passing through slotted tabs at the rear edges of the sheets. The lower end of this link or plate is inserted in the portion of the cross-slot **g** at right angles to the back of the retainer **F**, as shown in Fig. 30, while the upper end of the link or plate enters the narrow portion of the notch **h** and is locked in position by throwing the catch **H** around to close the open end of the notch. The bent arm **h'** over the top of the retainer 35 serves to prevent this link or plate from rising or becoming detached from the foot-piece in the handling of the files.

My improved retainer is adapted also for the reception and retention of still another 40 well-known form of binding device for the loose leaves, and of the construction illustrated in Patent No. 242,174. That device consists of a slotted yoke **K'**, combined with **T** projections at the backs of the leaves and 45 having bent upper and lower ends. This binding device is inserted in my improved holder by putting its lower end in the groove **f'** in the foot-piece of the holder **F**, while its corresponding upper end is pushed under and

behind the spring-catches **h** on the top piece 50 of the retainer, as will be readily understood on reference to Fig. 5.

It will thus be seen that my improved retainer can be applied to boxes intended for the reception of different well-known forms 55 of indexed filing-sheets, and that any of those forms of filing-sheets may be readily and conveniently put in place or removed, as desired.

It will be evident that the form of my retainer does not interfere with the use in the 60 case or filing-box containing it of loose leaves unprovided with any means of uniting them together.

I claim as my invention—

1. A retainer for the leaves of a filing-case, 65 said retainer having at one end a cross-shaped slot and having at the other a notch with a locking-catch.

2. A retainer for the leaves of a filing-case, provided with a foot-piece having a raised 70 portion containing a cross-shaped slot and a top piece with a notch and a locking-catch.

3. A retainer for the leaves of a filing-case, 75 having a foot-piece and a raised portion, leaving a groove behind it containing a cross-shaped slot, in combination with a top piece having a notch and locking-catch therefor and spring-catches on its under side.

4. A retainer for the leaves of a filing-case, having a slotted foot-piece, a notched top 80 piece with a locking-catch, and a holding-down finger.

5. A combination of a detachable headed pin with a retainer having a foot-piece provided with a cross-shaped slot, and a top piece 85 provided with a notch and a locking-catch.

6. A retainer for the leaves of a filing-case, 90 having a slotted foot-piece, and a top piece with a notch widened at its open end, and having a locking-catch for this notch.

In testimony whereof I have signed my name to this specification in the presence of two subscribing witnesses.
